TOOTHBRUSH.

Lawrence W. Campbell and Wilber P. Watson,
Clarksburg, W. Va.; said Watson assignor
to Ann Watson, Clarksburg, W. Va.

Application July 29, 1933, Serial No. 682,854

2 Claims. (Cl. 15—167)

This invention appertains to new and useful improvements in tooth brushes.

The principal object of the present invention is to provide a tooth brush wherein the head 5 of the brush is so constructed as to permit the bristle sets to yield to conform either with the outside of the teeth or with the inside.

Another important object of the present invention is to provide a tooth brush which can be 10 used efficiently for brushing the front side as well as the inner side of the teeth without any manual manipulation to change the curvature of the bristle set contact area.

Another important object of the present invention is to provide a brush which will readily 15 conform itself to the curvature of the surface against which it is placed.

These and various other important objects and 20 advantages of the invention will become apparent to the reader of the following specification.

In the drawings:

Figure 1 represents a top plan view of the 25 novel brush.

Figure 2 represents a side elevational view of the brush.

Figure 3 represents a side elevational view of the brush head, with the bristle sets curved for brushing the inside of teeth.

Figure 4 represents a side elevational view of the brush head, with the bristle sets disposed for cleaning the outside of teeth.

Figure 5 represents a cross sectional view taken substantially on line 5—5 of Figure 1.

Figure 6 represents a top plan view of one of the bristle set blocks.

Figure 7 represents a longitudinal sectional view through the head portion of the brush, with the bristle sets and blocks removed.

Figure 8 represents a sectional view taken substantially on line 8—8 of Figure 2, showing the bristle sets and blocks removed.

Figure 9 represents a longitudinal sectional view taken substantially on line 9—9 of Figure 1.

Figure 10 represents an enlarged cross sectional view taken substantially on line 10—10 of Figure 7.

Figure 11 represents a sectional view taken substantially on line 11—11 of Figure 5, and showing one form of bristle set.

Figure 12 represents a similar sectional view of a modification of the bristle set.

Figure 13 represents a similar sectional view to that of Figure 2, showing a slightly different form of bristle set.

Referring to the drawings, wherein like numerals designate like parts, it can be seen that numeral 5 represents the tooth brush handle, while numeral 6 generally refers to the brush head which includes a pair of elongated metallic members 7—7 each provided with an offset end portion. These offset end portions are denoted by 8 and are brought together and suitably anchored in the head end portion of the handle 5. This leaves the outwardly projecting end 10 portions of the members 7—7 slightly spaced apart, as is clearly shown in Figure 8.

Each of these members 7—7 is provided with a plurality of transversely extending slots 9 and on the outside of each of these members 7 and 15 between the said slots are the rectangular boss-like guides 10.

As is clearly shown in Figures 11, 12 and 13, numeral 10 represents the block of a bristle set 20 and there are an equal number of bristle sets 11 and blocks 10 to the number of slots 9 in each of the members 7—7. The blocks 10 are disposed along the outer sides of the members 7—7 and as is clearly shown in Figure 5, pins 12 extend through the corresponding slots 9 in the 25 members 7—7 and each end of each of these pins extends into a corresponding block 10. Thus the blocks and sets are supported in pairs, a pair being located on each of the pins 12.

Located between the external extensions of the 30 members 7—7 is the elongated hair spring 13 which has its hooked ends 14 hooked over the end pins 12. The major portion of this spring 13 is interposed between the pins 12 and the pair of rivets 15—15, which rivets are preferably 35 located between the second and third sets, counting inwardly from each end of the head, as is clearly shown in Figure 9.

By referring to Figure 6, it can be seen that each of the blocks 10 is provided with notched-out portions 16—16 which accommodate the guide bosses 9 so that the motion of the blocks will be transversely of the members 7—7.

As can be clearly seen in the drawings, the bristle sets will be normally retained in the position shown in Figure 9. When it is desired to brush the outside of the teeth, the bristle sets are pressed against the teeth and as the intermediate bristle sets are pressed against the teeth, their corresponding blocks 10 will be slid across 50 the members 7—7 and the action of their pins 12 against the hair spring 13 will cause the bristle sets at the ends of the head to move outwardly in the reverse direction so that the bristle sets will assume the formation shown in Figure 55

4. In this position, which takes place automatically, the bristles are properly set so that all of the bristle sets will function usefully.

In cleaning the inside of the teeth, the end bristle sets will engage the teeth and will move their blocks 10 transversely across the members 1-1 so that their pins will press against the spring 13 and cause an inflex of the spring 13, which will force the intermediate bristle sets 10 outwardly so as to afford a convex contact surface such as is shown in Figure 3, thus affording efficient use for all of the bristles of the brush.

In Figure 12, the bristle set and block 10 is slightly modified by placing the pin 12 directly through the inner ends of the bristles, while in Figure 13, the pin 12 is fixed in the block 10 by extending into the bristles slightly outward of the inner ends of thereof.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A tooth brush comprising a handle, a head

structure, said head structure being provided with a plurality of transversely extending slots, a plurality of bristle mounts, pins for slidably connecting the said bristle mounts to the head at the said slots, and means between the said bristle mounts whereby pressure on the intermediate bristle mounts will cause the outermost bristle mounts to move outwardly, while pressure on the outermost bristle mounts will cause the intermediate bristle mounts to move outwardly. 10

2. A tooth brush comprising a handle, a head structure, said head structure being provided with a plurality of transversely extending slots, a plurality of bristle mounts, pins for slidably connecting the said bristle mounts to the head 15 and being disposed through the said slots, and an elongated spring element disposed across the said pins and having limiting means therefor on the head inwardly of the ends of the said spring so that pressure on the intermediate bristle mounts will cause the outermost bristle mounts to move outwardly, while pressure on the outermost bristle mounts will cause the intermediate bristle mounts to move outwardly. 20
